(57) **CLAIM**

The ornamental design for an ergonomic arm support for computer operators, as shown and described.

DESCRIPTION

FIG. 1 is a perspective view of an ergonomic arm support for computer operators according to our new design;

FIG. 2 is a top view thereof;

FIG. 3 is a bottom view thereof;

FIG. 4 is a front view thereof;

FIG. 5 is a back view thereof;

FIG. 6 is a right side end view thereof; and,

FIG. 7 is a left side end view thereof.
